UNITED STATES PATENT OFFICE.

MORRIS BROWNSTEIN, OF CHICAGO, ILLINOIS, ASSIGNOR TO EDWARD KATZINGER COMPANY, OF CHICAGO, ILLINOIS, A CORPORATION OF ILLINOIS.

GARBAGE-CAN.

1,163,886.

Specification of Letters Patent. Patented Dec. 14, 1915.

Application filed February 5, 1915. Serial No. 6,245.

To all whom it may concern:

Be it known that I, MORRIS BROWNSTEIN, a citizen of the United States, residing at Chicago, in the county of Cook and State 5 of Illinois, have invented a new and useful Improvement in Garbage-Cans, of which the following is a specification.

My invention relates to receptacles adapted to contain garbage, ashes and other waste 10 materials.

The object of this improvement is the provision of a suitable receptacle of the character mentioned having a cover closely fitting thereon and foot operable means whereby 15 the cover is easily moved to open position to permit articles to be discharged into the receptacle.

A further object is the provision of such a device having a cover adapted to be closed 20 by gravity.

Further objects will appear hereinafter.

The invention consists in substantially the combinations and arrangement of parts hereinafter described, shown in the accompanying drawing forming a part of this specification, and more especially set forth in the appended claims.

In the drawing—Figure 1 is a side elevation of a garbage can embodying my invention; and Fig. 2 is a plan view of the same.

My invention may be embodied in receptacles of various sizes and shapes as desired. The particular receptacle shown is cylindrical in form and provided with a cover 5 substantially conical in form. The shape of the cover may be varied when so desired but I prefer to use one of the form shown for the reason that when placed outside or not under cover it will shed water and is more easily kept clean. I have shown the cover as being formed in two parts, but when so desired the cover may be formed in a different number of parts in accordance with the appended claims.

The receptacle 3 has its upper edge in substantially the same plane, and supported on the upper edge of the receptacle is a cover made up of two parts 4 and 5. The part 4 is secured to a portion of the top edge of receptacle 3 by means of solder or in any other desired and suitable manner. The part 5 is movably mounted with respect to the part 4 and receptacle 3 and is preferably provided with an edge portion 6 struck up forming a bead and fitted over the adjacent

edge of part 4 in a manner so that it will shed water, or the like. The edge of part 5 which rests on the top of receptacle 3 when in normal position, is fitted to and extends slightly over the top edge of receptacle 3 in a manner to prevent water, or the like, entering the receptacle 3 when the part 5 is closed or in normal position. On the part 5 I provide a handle 7 by means of which said part may be moved to open position.

I provide hinges for pivotally mounting the part 5 on the receptacle 3 and preferably form the hinges in such a manner that when the part 5 is swung to open position the latter will be swung away from part 4 and completely expose the opening under part 5 to the receptacle in order to provide means for easily placing material in the receptacle 3 when the part 5 is in open position. Each of the hinges is made up of a portion 8 secured to the receptacle and extending above the upper edge thereof, and a portion 9 secured to the part 5 and extending rearwardly from the edge thereof and pivoted to the upper end of portion 8. This arrangement provides pivotal points for the part 5 which are in a line outside of the part 5 and above the receptacle 3. This arrangement provides means for effecting proper opening of the part 5 as above described.

One of the hinges is provided with an arm 10 on its portion 9 which extends beyond the pivotal point of the hinge and in a direction away from part 5 of the cover, so that a downward pull on the outer end of 90 said arm will cause an upward movement of portion 9 and part 5.

Near the bottom of receptacle 3 I pivot a foot lever 11, as at 12. The free end of the foot lever 11 is connected by means of a connecting link 13 with the free end of arm 10 so that upon downward pressure being applied to foot lever 11 the part 5 of the cover will be moved to open position.

Owing to the particular formation of the 100 hinges of part 5 and the particular position of foot lever 11 part 5 will not be permitted to be brought quite to a vertical position so that upon pressure being withdrawn from foot lever 11 the weight of part 5 will cause 105 said movable parts to be returned to their normal positions.

When so desired, the receptacle 3 may be provided with a handle 14 near its lower side to facilitate handling the can, such as 110

in emptying the can. The receptacle 3 may further be provided with a bail 15 of any usual or preferred construction, to facilitate moving the can from one place to another.

5 While I have illustrated and described the preferred form of construction of my invention, I do not desire to be limited to the precise details set forth but desire to avail myself of such variations and changes as 10 come within the scope of the appended claims.

What I claim is:

15 1. A garbage can comprising a receptacle; a cover made up of two parts, one of the parts being secured to said receptacle and the other part being movable with respect to the latter; said movable part having a bead struck up in one edge and fitting over the adjacent edge of the stationary part forming a substantially water-tight joint between the parts, a pair of hinges connecting said movable part to the receptacle and adapted to cause the movable part to swing away from the top of the receptacle and the part secured to the latter; and manually operable means connected with one of the hinges and adapted to cause movement of the movable part of the cover.

20 2. A garbage can comprising a receptacle; a cover made up of two parts, one of the parts being secured to said receptacle and the other part being movable thereon; a pair of hinges connecting said movable part to the receptacle, each of the hinges being 25 made up of two portions, one of the portions being secured to said movable part and extending beyond the edge of the latter, and the other portion being secured to the receptacle, extending above the top thereof

and pivoted to the first mentioned portion; an arm on one of the first mentioned portions of the hinges and extending beyond the pivotal point of the hinge; a foot operable lever mounted on the receptacle; and a connecting rod connecting said arm with said 45 lever.

3. A garbage can comprising a receptacle; a cover made up of two parts, one of the parts being secured to the receptacle and the other of the parts being movable with 50 respect to the latter; hinges connecting the movable part of the cover with the receptacle, each of said hinges comprising two parts, one of said parts being a member secured to and extending above the receptacle and the other of said parts being two members disposed on opposite sides of and pivotally connected to the first mentioned part, one of said two members being shorter than the other and both of such members being secured to the cover, said two members extending over the adjacent edge of the movable part of the cover providing means whereby said movable part of the cover moves away from the stationary part of the cover and the receptacle upon moving on its hinges; and pedal operable means connected with one of the hinges for moving the movable part of the cover on such hinges.

In testimony whereof I have signed my name to this specification, in the presence of two subscribing witnesses, on this 2nd day of February A. D 1915.

MORRIS BROWNSTEIN.
